UNITED STATES PATENT OFFICE.

JAMES HAMILTON, OF NEWBURG, NEW YORK.

DESIGN FOR A SPOOL-STAND.

SPECIFICATION forming part of Design No. 28,797, dated June 7, 1898.

Application filed January 6, 1898. Serial No. 665,858. Term of patent 14 years.

To all whom it may concern:

Be it known that I, JAMES HAMILTON, a citizen of the United States, residing at Newburg, in the county of Orange and State of New York, have invented and produced a new and original design for a Spool-Stand, of which the following is a specification, reference being had to the accompanying drawings, forming a part thereof.

Figure 1 is a view in front elevation, showing my new design. Fig. 2 is a sectional view taken on the line X X of Fig. 1.

As shown in the drawings, the leading or material features of my design consist of a base A, having the outline of a shield, with

the central portion of its face raised in the form of a cushion B, and a series of pins projecting from said face in a row following substantially the contour of the outer edge of the shield.

Having thus described my invention, what I claim as new, and desire to secure by Letters Patent, is—

The design for a spool-stand as herein shown and described.

JAMES HAMILTON.
